ADJUSTABLE STANDARD

Albert W. Dixon, Cincinnati, Ohio, assignor to
The Alvey-Ferguson Company, Cincinnati,
Ohio, a corporation of Ohio

Application June 19, 1944, Serial No. 540,988

4 Claims. (Cl. 248—351)

This invention relates to portable adjustable standards, particularly as pedestals or supports for conveyor tracks or movable sections thereof, as of the roller or wheel type, the track being inclined for dispatching by gravity, merchandise placed thereon. The track is usually of straight or curved sections so that the dispatching line and location can be readily changed or altered to meet different dispatching destinations. It is therefore necessary that the standards be adjustable for height variation.

An object of the invention is to provide a standard of extreme simplicity in construction, easily and cheaply fabricated from angle bar and tube stock material, sturdy in structure and having a leg base preferably in tripod arrangement, resisting to shift and a stanchion or post adjustable within the base.

Another object is to provide for a standard of a plurality of angle bars, an parallelism, traversing a tubular support and secured and locked therein by a cone pointed screw carried by the support to intersect and oppositely force the bars in binding engagement with the interior of the tube for a quick and secure height adjustment of the standard and to form a simple and inexpensive structure of exceptional strength.

Various features and advantages and features of the invention will be more fully set forth in the following description of the accompanying drawing forming a part hereof and exemplifying a preferred embodiment, in which:

Figure 1 is a side elevation of the improved adjustable standard.

Figure 2 is a section on line 2—2, Figure 1.

Figure 3 is an enlarged section on line 3—3, Figure 1.

Figure 4 is a section on line 4—4, Figure 3.

Figure 5 is an end view of the head end of the stanchion.

Figure 6 is an enlarged section on line 6—6, Figure 5.

Referring to the drawing, the standard as illustrated is principally constructed of sections of angle bar stock, consisting preferably of a tripod base 1 and a stanchion 2, adjustably mounted within the base. The base comprises a plurality of legs 3, of angle bar sections, in tripod arrangement, with the apex of the bars outward adapting the flanges for one end of the bars to straddle and bear against the exterior of a tube section 4, as a hub or axis for the base, through which the stanchion traverses and to which it is clamped. The legs are preferably welded to the hub 4, and toward their lower end are tied together, against

spreading, by a sheet metal plate 5, of triangular outline, with each of its points respectively engaged into the channel of a relative angle bar leg and welded therein. The foot end of each leg bar has its flanges trimmed to a floor plane, although they could be square cut for a pointed claw hold upon the floor. The tie plate 5 has an aperture 6, therethrough, coaxially with the hub as a clearance for the lower end of the stanchion, so as not to limit its descent adjustment.

The stanchion is composed of a pair of companion angle bar sections 7, 7, preferably arranged with the flanges opposing each other and slightly spaced apart, and both, at their upper end are joined to a transverse head bar 8, preferably at a point central of the length of the head bar. The head bar, correspondingly, comprises an angle bar section, with its apex upward, whereby the flanges of the bar straddle the upper end of the stanchion bars and the parts welded together.

The stanchion composed of a plurality of parallel angle bars is extremely sturdy, capable of sustaining heavy loads without flex, aside from its simple and economical fabrication. The bars in their slightly spaced or separated relation provide a longitudinal opening for the full length of the bars for the reception of a pair of guide rods 9, 9, diametric of the hub and at their opposite ends fixed thereto. The rods 9, non-rotatively confine the stanchion within the hub and govern its insertion therein, so that the spacing or line of division is always brought and maintained in alignment and registration with the cone pointed end of a clamp screw 10. The clamp screw 10, has its outer end bent at an angle to provide a crank hand hold.

The cone pointed end of the clamp screw 10, wedgingly engaged with the edges of relative opposing flanges of the angle bars of the stanchion and in tightening spreads the bars apart at one longitudinal end, while the opposite ends are maintained and in bearing contact with the struts or separator rods 9, within the hub, to fulcrum thereon and force the apexes of the bars into impinging contact with the interior or bore of the hub, binding the parts together for the full contacting length, resisting any possible slip of the stanchion under heavy loads imposed thereon, and more effectively than is possible by the conventional method of having the pointed end of a clamp or set screw engaging against a flat or peripheral surface of a stanchion.

With one flange of each angle bar in bearing

contact with a plurality of spaced struts within the hub and the other or second flange of the bar engaged by the conical end of the clamp screw interveningly of the struts, the bars under the clamping pressure of the screw will be simultaneously forced outwardly, each in an arc of movement bringing the apex of each bar into biting contact with the full length of the bore of the hub, insuring a non-slipping hold. There is no opportunity for the bars to be shifted out of plumb or into a canting position.

The upper end of the bars 7, 7, of the stanchion are fixed together and determinately spaced by a tie plate 11, combining the same as an integral unit, including the transverse head bar 8.

The standard is equally applicable for adjustably supporting either curved or straight roller conveyor track sections, is comparatively light in weight and exceptionally strong. A conveyor line can be set up and adjusted for proper pitch in a few minutes and a change in the line can be readily affected to accommodate for different loading and unloading destinations.

The hub of the base is illustrated as provided with a pair of guide rods or struts 9, 9, respectively located at opposite ends of the hub, it however has been experienced that a single strut preferably located at the upper end of the hub will suffice.

In the preferred form of tripod base, the legs are not relatively uniformly spaced about the hub, and in plan one pair are in closer relation and correspondingly obliquely to the head bar of the stanchion so as to stretch out as from one side thereof while the third leg is at right angles to the head bar and as extending from an opposite side of the head centrally opposing to the others as a pair. This arrangement offers greater stability against tilt. The struts or guide rods 9, are disposed to extend in a direction in relation to the legs to insure insertion of the stanchion with the head bar extending in direction at an angle thereto and therefore appropriately to the leg set up.

Having described my invention, I claim:

1. An adjustable standard, comprising: a base

of tripod form having its legs fixed to and extending from a central hub, and a stanchion traversing the hub and composed of a pair of spaced bars fixed together at one end and the hub having a clamp screw for wedging between the bars for forcibly binding the same within the hub.

2. An adjustable standard, comprising: a base having a central vertical hub, a stanchion composed of a pair of angle bars traversing the hub and disposed in opposing relation to extend their apices outward, and a clamp screw carried by the hub having a conical end engaged between the bars to spread them apart and force their apices into biting contact with the hub.

3. An adjustable standard, comprising: a base having a vertically extended hub, the hub having struts diametrically across its bore, a stanchion composed of a pair of angle bars, traversing the hub and respectively at relative opposite sides of the struts and a clamp screw carried by and extended into the hub in alignment with the struts for engaging with the bars at a line of division thereof to simultaneously force the same outwardly into binding contact with the interior hub, the struts governing the insertion of and maintaining their line of division in registry with the clamp screw.

4. An adjustable standard, comprising: a base of tripod form having a vertically extended hub with a strut extending diametrically through its bore, a stanchion of T-head form composed of a pair of spaced parallel bars at one end joining with a transverse head bar, the parallel bars slidably engaged through the bore of the hub of the base, respectively at relative opposite sides of the strut, and means extending into the hub for engaging the bars at a line of division to simultaneously force the same outwardly into binding contact with the hub, the strut governing the insertion of the bars with their line of division in registry with said means and appropriately directioning the T-head of the stanchion to the legs of the tripod base.

ALBERT W. DIXON.
